UNITED STATES PATENT OFFICE.

HERBERT S. MILLS, OF CHICAGO, ILLINOIS.

MOTOR.

No. 846,439.

Specification of Letters Patent.

Patented March 5, 1907.

Original application filed February 27, 1905, Serial No. 247,492. Divided and this application filed November 4, 1905.
Serial No. 285,877.

To all whom it may concern:

Be it known that I, HERBERT S. MILLS, a citizen of the United States, residing at Chicago, in the county of Cook and State of Illinois, have invented a new and useful Improvement in Motors, of which the following is a specification.

My invention relates particularly to machines employing an electric motor for motive purposes, although the invention is applicable to machines employing any other form of motor as a primary source of power.

My primary object is to provide mechanism wherein provision is made for winding the spring which serves to actuate a machine element, such as the record of a phonograph, by means of a motor which will operate for a predetermined period of time when set in motion, thereby to give to the spring serving to

actuate said element a predetermined tension.

In the accompanying drawings my invention is shown applied to a phonograph of well-known type employing a disk-form record.

In the drawings, Figure 1 represents a side elevational view of a phonograph and the mechanism applied thereto in accordance with my invention; Fig. 2, a reverse side elevational view of the same; Fig. 3, a plan view of the same; Fig. 4, a front view of the same; Fig. 5, a broken section taken, as indicated, at line 5 of Fig. 1, showing a controlling-wheel, which serves to control the circuit of the electric motor shown, and a stop-actuating lever employed, said view showing also the operative parts adjacent to said wheel; Fig. 6, a rear view of the machine; Fig. 7, a view similar to Fig. 5, showing a different position of the parts; Fig. 8, a broken sectional view taken, as indicated, at line 8 of Fig. 2; Fig. 9, a similar view showing the parts in a different position; Fig. 10, a view showing the parts in still another position; Fig. 11, a broken section taken, as indicated, at line 11 of Fig. 10; and Fig. 12, a similar view showing the parts in a different position.

The construction illustrated comprises a phonograph D of known general construction, having a disk-form record D', a record-bearing disk D², a record-bearing actuating-shaft D³, actuated by a pinion D⁴, a cylinder D⁵, equipped with the usual spring (not shown) and with a gear D⁶, a pinion D⁷,

driven by the gear D⁶ and in turn driving a gear D⁸, meshing with the pinion D⁴, a governor D⁹, actuated by gears D¹⁰ from the shaft D³, a horizontal winding-shaft D¹¹, equipped, Fig. 6, with a pinion D¹², meshing with a pinion D¹³, through the medium of which the spring is wound in the usual manner, and a reproducer D¹⁴, mounted upon an arm D¹⁵ and co-operating with the record D'; an electric motor E in an electric circuit E', energized from any suitable source and equipped with normally separated contact members E² E³; a worm E⁴ on the shaft of the motor E and meshing with a worm-wheel E⁵, secured on the winding-shaft D¹¹; a contact-actuating lever F, Figs. 3, 8, 9, and 10, equipped with an insulation-finger f, against which the contact E³ bears; a controlling-wheel F' for the lever F, bearing a lateral annular flange f', provided with a notch f², adapted to receive a lug f³, on the lever F, said wheel being provided peripherally with ratchet-teeth f⁴; a spring-held actuating pawl F², joined by a pivot f⁵ to the wheel E⁵ and serving to actuate the wheel F'; a spring-actuated cam-retracted member F³, through the medium of which the member F' is actuated in the operation of closing the motor-circuit, the member F³ being actuated by a spring f⁶ in said closing operation; a spring F⁴, tending normally to pull the free end of the member F³ forward, so that when said member is withdrawn by the controlling-wheel, which will be later described, a shoulder f⁷ will engage a shoulder f⁸ on a loop or guide x on the lever F, thereby to effect movement of the lever F when the member F³ returns under the action of its spring; a cam F⁵, Figs. 6, 11, and 12 on the member F³, with which engages a cam F⁶, formed integrally with the wheel F', whereby the free end of the member F³ is forced rearwardly after the wheel F' starts to rotate, and the lug f³ is engaged by the flange f' of the wheel; a stop-actuating cam F⁷ on the member F³, which serves to elevate a stop F⁸, whose upper end will thus be brought into the path of stops on the record-supporting plate D²; a wheel G, Figs. 5 and 7 serving, through the medium of a lever G', to withdraw the member F³ against the tension of its spring at the proper time and serving also, through the medium of a lever G² and a pawl G³, to withdraw the latch G⁴ of a stop-actuating lever G⁵,

a gear G^6 , formed integrally with the wheel G and actuated by a pinion G^7 , secured on a shaft G^8 , equipped with a gear G^9 , which meshes with the gear D^6 , by which it is actuated; a stop H , connected with the lever G^5 , Figs. 1 and 3 which stop coacts with stops on the record-supporting disk D^2 , and a pivotally-supported reproducer-shifter J , connected by a member J' , Fig. 4, with a stud J^2 , carried by the elbow of the lever G^2 , Fig. 7.

The general construction of the phonograph need not be described more at length.

The record D' and its supporting-plate D^2 are readily removable from the shaft D^3 . For the purposes of the present invention I have provided the member d^3 on its lower side with yieldingly substantially radial stops d , whose outer ends project somewhat beyond the circumference of the disk, as shown in Fig. 3. These stops may be engaged by either, or both, of the stops F^8 and H . The function of the stop H is to control the movement of the record of the phonograph in ordinary use, and in coin-controlled machines the stop H is actuated ordinarily by a coin through the medium of the lever G^5 , the coin being directed to the free end of the lever by a chute a , as indicated by dotted lines in Fig. 1. The function of the stop F^8 is to prevent further rotation of the record after the machine has once operated until the motor has been set in operation to rewind the spring of the phonograph, whereby a desirable tension is always maintained on the phonograph-spring, the spring never being allowed to run down. The worm-driven wheel E^5 takes the place of the winding-key of the ordinary manually-wound phonograph of this type.

The motor-circuit may be provided with a fuse. (None shown.) The contacts E^2 E^3 preferably comprise two normally separated spring-metal members, the member E^3 being capable of being forced into engagement with the member E^2 and returning under its own resiliency to the open position.

The contact-actuating member F is equipped near its pivot f^9 with a short arm f^{10} , and the spring F^4 joins the arm f^{10} to the free end of the member F^3 . Thus it will be understood that the lug f^3 tends normally to enter the recess f^2 in the flange f' of the wheel F' . The wheel F' is mounted on a stud f^{11} , carried by a frame member f^{12} . Said wheel is guarded against retrograde movement by a spring f^{13} . The pawl F^2 is held in engagement with the ratchet-teeth f^4 by a spring f^{14} . The member F^3 has one end freely movable in the loop x of the member F . The stop F^8 is in the form of a vertically-movable rod having a collar s near its lower end, Fig. 4, which rests upon a guide s' and holds the lower end of the stop high enough to permit the cam F^7 to pass beneath it during the movement of the member F^3 under the action of its spring, as indicated at Fig. 10.

The wheel G is provided on its front surface with a cam-lug g , adapted to engage the upper end of the lever G' and actuate said lever during each revolution of said wheel. The parts are so timed that the wheel G makes one revolution by about the time the record has been completely traversed by the stylus of the reproducer. When the lever G' is relieved from the action of the cam-lug g , the member F^3 is permitted to return under the action of its spring and close the motor-circuit, whereupon the circuit is maintained closed the allotted period by the wheel F' , the cam F^6 whereof operates in the meantime to release the shoulder f^7 of the member F^3 from the shoulder f^8 of the member F . The wheel G has a smooth circumferential surface g' , upon which rides a roller g^2 , carried by the member G^2 , the periphery of the wheel being provided with a recess g^3 , which the roller may enter after the wheel completes its revolution. The parts are so timed that the roller will enter the recess g^3 an instant before the cam-lug g releases the lever G' , and the lower end of the lever G' is provided with a locking-shoulder g^4 , which engages a shoulder g^5 , with which the member G^2 is provided, so that although the wheel G may allow the member G^2 to rise slightly before the member G^2 is released from the lug g this action nevertheless will not be permitted to occur until after movement of the lever G' . The lever G^5 has its free end held normally elevated by a spring g^6 , as shown in Fig. 1. The latch G^1 is provided with a locking-shoulder g^7 , which corresponds with the elevated position of the lever G^5 , and a locking-shoulder g^8 , which corresponds with the depressed position of said lever. The pawl G^3 is connected by a pivot g^9 with the lever G^2 , and is provided with a hook g^{10} , adapted to engage a lug g^{11} , with which the locking-pawl G^4 is provided. The pawl G^4 is supported from the frame of the machine on a pivot g^{12} and is provided with a short arm connected by a spring g^{13} with the pawl G^3 , whereby the tendency of the lower end of the pawl G^4 is to move outwardly and the tendency of the free end of the pawl G^3 is to move upwardly. On the frame is provided a stop g^{14} , which is engaged by the pawl G^3 to cause it to release its hold upon the pawl G^4 during the upward movement of the free end of the lever G^2 . The purpose of this action is to permit the pawl G^4 to assume its normal condition in readiness to lock the lever G^5 when the latter is again depressed. The spring g^{15} , connected with the lever G^2 and with a projection g^{16} , Fig. 1, on a frame member, tends normally to elevate the free end of said lever. The stop H comprises a vertically-movable bar provided with a slot, through which passes a stud h , supported by the frame. The reproducer-shifter J comprises a frame j , supported on a horizontal pivot j^2 , the

member J' having pivotal connection j^3 with the member j in front of the pivot j^2 . The front portion of the member J is equipped with a cam j^4 , having an inclined surface j^5 , which tends normally to hold the arm D^{15} of the reproducer over against an adjustable spring-stop j^6 at one side of the frame j , whereby the reproducer is held in a proper position to be lowered upon the record at its outer margin. When the stop-actuating lever G^5 is depressed and the spring-driven train of the phonograph allowed to operate the phonograph, the wheel G is caused to turn, owing to its connection with the driving-train of the phonograph, and the roller g^2 is forced out of the recess g^3 in said wheel, being moved from the position shown in Fig. 5 to the position shown in Fig. 7. This immediately depresses the front end of the reproducer-shifter through the medium of the connecting member J' , which is actuated by the lever G^2 . During the revolution of the wheel G the lever G^2 is held depressed, so that the cam j^4 is held out of the way of the arm D^{15} until the reproducer has completed its travel across the record, whereupon, the lever G^2 rising, the cam j^4 is elevated, thereby raising the reproducer and causing it to shift back to its starting position with the arm D^{15} rising against the yielding stop j^6 .

The frame which supports the phonograph and the winding-motor may be of any suitable construction. Preferably it comprises integral bottom members p and standards p' , the standards being surmounted by the usual top plate p^2 , which supports the main portion of the mechanism proper and in which the record-actuating shaft D^3 is journaled.

The mode of operation may be briefly summarized thus: The motor E is preparatorily operated to give the spring of the spring-driven train of the phonograph a desired tension, which tension is greater than is actually required to turn the record until the reproducer has fully traversed it, thereby assuring adequate power and a desired rate of rotation of the record at all times. The motor-circuit may be closed in any suitable way to effect the initial winding of the phonograph-spring. The wheel F' is preparatorily adjusted, so that after the spring of the phonograph has been preparatorily wound the notch f^2 receives the lug f^3 of the contact-shifter F , whereby the wheel F' is locked and the motor-circuit left normally open. Assuming the friction-brake, which constitutes a portion of the governor D^6 and is well understood in the art, to be preparatorily set to control the rate of rotation of the record and assuming the spring of the spring-motor of the phonograph to be properly wound, the lever G^5 may be depressed, as by means of a coin, thereby to withdraw the stop H and permit the record to turn. As soon as the

record begins to turn the wheel G , driven from the spring-motor, begins to turn also and depresses the lever G^2 , thereby tilting the front end of the reproducer J downwardly and allowing the reproducer to drop until the stylus engages the record. As the wheel G nears the end of its revolution the cam g operates the lever G' and withdraws the member F^3 from the position shown in Fig. 8 to the position shown in Fig. 9, the spring F^4 operating at the same time to draw the free end of the member F^3 forwardly, so that the shoulder f^1 will be in position to engage the shoulder f^8 upon the return movement of the member F^3 . When the cam-stud g releases the lever G' , the spring f^6 returns the member F^3 to approximately its normal position, thereby forcing the member F outwardly and closing the motor-circuit. In the movement of the member F the wheel F' is unlocked, and immediately the winding-wheel E^5 is set in operation the pawl F^2 begins to turn the wheel F' . The first effect of the movement of the wheel F' is to bring the flange f^1 alongside the lug f^3 in readiness to prevent return of the member F until the wheel F' has completed a revolution. In the first movement of the wheel F' also the cam F^6 engages the projection F^5 on the member F^3 , thereby moving the free end of said member rearwardly and effecting its release from the member F . After this release of the member F^3 from the position shown in Fig. 10 the stop F^8 drops to the position shown in Fig. 8, where it forms a stop for the member F^3 . It will be seen, therefore, that when the wheel F' completes its rotation the member F is free to swing inwardly until the lug f^3 has fully entered the recess f^2 . Returning now to the action which occurred when the wheel G started to rotate, it should be stated that the effect of depressing the lever G^2 was to cause the pawl G^3 to interlock with the pawl G^4 , and it will be seen, therefore, that when the wheel G completes its revolution and the roller G^2 enters the recess g^3 the pawl G^4 will be caused to release the lever G^5 , (with which it made engagement when the lever G^5 was depressed,) and an instant later the pawl G^3 will be caused to release the pawl G^4 , leaving the latter free to engage the lever G^5 upon a subsequent depression thereof. It should be pointed out also that the stop F^8 , which is normally depressed and free from the path of the stops d on the record-supporting disk, has its lower end engaged by the inclined surface of the cam F^7 when the member F^3 returns under the action of its spring to force the contact-actuating member F outwardly, and when the cam F^6 forces the free end of the member F^3 rearwardly the stop F^8 drops off the cam F^7 and occupies the position shown in Fig. 9. Thus it will be seen that the stop F^8 is held in an elevated position, preventing the rotation of

the record until the electric motor has started to rewind the spring of the spring-motor, so that said spring is prevented from running down. It should be added, as is apparent from Fig. 3, any excessive winding of the spring of the spring-motor would be relieved by a rotation of the record, the stops *d* yielding to pass the stop *H*, thereby preventing breakage. Moreover, the yielding of the stops *d* breaks the shock which otherwise would occur when the record is stopped at the end of the operation.

It will be obvious that many changes in details of construction within the spirit of my invention may be made. Hence no undue limitation should be understood from the foregoing detailed description. It is believed to be novel to employ what for the purpose of this application will be termed a "primary motor," operated from any suitable source of power to wind a spring-motor, the primary motor being automatically set in operation by the action of the spring-motor and operating to produce a predetermined winding effect upon the spring-motor and finally being automatically stopped. It is to be understood, therefore, that the appended claims are intended to cover the invention in its widest application, regardless of the particular use to which the invention may be put.

As is well understood, electric currents of the same nominal voltage vary at different plants throughout the country, so that an electric motor cannot be used without great limitations for the direct actuation of a phonograph the number of the rotations of the record in which must be subject to very little variation. Furthermore, the provision of means for quickly and readily winding the spring-motor of a phonograph of the type herein shown and for insuring the proper degree of winding is regarded as of great importance.

45 The present application constitutes a division of application Serial No. 247,492, filed by me February 27, 1905.

What I regard as new, and desire to secure by Letters Patent, is—

50 1. The combination with a spring-motor of an element operated thereby, means for normally holding said element against rotation, a winding-motor, and mechanism operated by the spring-motor and connected with said holding means and serving to start the winding-motor after the release of said element from its holding means, for the purpose set forth.

60 2. The combination of a spring-motor, an element driven thereby, a stop coacting with said element, a winding-motor, starting and stopping mechanism for the winding-motor controlled by the spring-motor, and a locking device for said stop controlled by the 65 spring-motor, whereby movement of said

element for a predetermined period is permitted and rewinding of the spring-motor effected, for the purpose set forth.

3. The combination of a spring-motor, an element driven thereby, a stop coacting with 70 said element, an electric winding-motor having a circuit, circuit-controlling mechanism actuated by said spring-motor, and mechanism controlled from said spring-motor serving to withhold said stop for a predetermined 75 period to permit rotation of said element, for the purpose set forth.

4. The combination with a winding-shaft of a spring-motor, of a winding-motor geared thereto, a circuit-controlling wheel, and a 80 pawl actuated with said winding-shaft and serving to actuate said wheel, for the purpose set forth.

5. In motor-controlling mechanism of the character described, the combination with a 85 spring-motor and an electric winding-motor, of a spring-held slideable circuit-controlling member *F*, a lever *G'* serving to retract the member *F*, and a rotary wheel *G* equipped with a cam serving to operate said lever. 90

6. In mechanism of the character described, the combination of a spring-motor, an element actuated thereby, a stop-carrying lever, a stop carried thereby and coacting with said element, a locking-pawl *G* for the 95 stop-carrying lever, a lever *G'*, a spring-held pawl carried thereby and coacting with the pawl *G*, and a wheel *G* controlling the lever *G'*, for the purpose set forth.

7. The combination with a spring-motor 100 and a winding-motor, of an element actuated by the spring-motor, a yieldingly-held stop normally restraining said element from moving, a normally retracted stop for said element, and mechanism controlled from the 105 spring-motor serving to hold said first-named stop retracted, after withdrawal, for a period and then project the second-named stop and also start the winding-motor, for the purpose set forth.

8. The combination with a spring-motor and a winding-motor, of an element actuated by the spring-motor, a yieldingly-held stop normally restraining said element from moving, a normally retracted stop for said element, a lock for holding said first-named stop retracted for a period after withdrawal from said element, a wheel controlling said lock, and means controlled by said wheel for projecting the second-named stop and starting the winding-motor, for the purpose set forth. 115

9. The combination with a spring-motor, of an element operated thereby, holding means normally restraining said element from rotation, an electric winding-motor 125 having a circuit, means for effecting withdrawal of said holding means to permit rotation of said element under the action of the spring-motor, means for automatically moving said holding means again into position to 130

restrain said element from rotation, and circuit-controlling means operated by the power of the spring-motor, whereby the winding-motor is set in operation after said spring-motor has operated for a predetermined period.

10. The combination with a spring-motor, of an element operated thereby, means for normally holding said element against rotation, an electric winding-motor having a circuit, means for effecting release of said element to permit rotation thereof, and circuit-controlling means operated by the power of the spring-motor to close the circuit after the spring-motor has operated said element for a predetermined period.

11. The combination with a spring-motor, of an element operated thereby, a stop whereby rotation of said element may be restrained, means for retracting said stop and maintaining it in a retracted position for a predetermined period to permit rotation of said element for a predetermined period, an

electric winding-motor having a circuit, and circuit-controlling means operated by the power of the spring-motor to close the circuit after the spring-motor has operated said element for a predetermined period.

12. The combination with a spring-motor, of an element operated thereby, a stop whereby rotation of said element may be restrained, means for retracting said stop and maintaining it in a retracted position for a predetermined period to permit rotation of said element for a predetermined period, means for causing the stop to resume its position for restraining said element, an electric winding-motor, and circuit-controlling means operated by the power of the spring-motor to close the circuit after the spring-motor has operated said element for a predetermined period.
